UNITED STATES PATENT OFFICE.

JOHN H. WALKER, OF LEXINGTON, KENTUCKY.

TROLLEY.

SPECIFICATION forming part of Letters Patent No. 761,567, dated May 31, 1904.

Application filed December 24, 1903. Serial No. 186,502. (No model.)

To all whom it may concern:

Be it known that I, JOHN H. WALKER, a citizen of the United States, residing at Lexington, in the county of Fayette and State of Kentucky, have made certain new and useful Improvements in Trolleys, of which the following is a specification.

My invention is an improvement in trolleys, and has for an object, among others, to provide a contact supplemental to the wheel in order to provide for taking off more current than can be ordinarily effected by the use of the wheel alone; and the invention consists in certain novel constructions and combinations of parts, as will be hereinafter described and claimed.

In the drawings, Figure 1 is a side elevation, partly broken away, of a trolley embodying my invention. Fig. 2 is a top plan view thereof. Fig. 3 is a detail cross-section on about line 3 3 of Fig. 2. Fig. 4 is a section on about line 4 4 of Fig. 1. Fig. 5 is a detail perspective view of the outer side of one of the inner washer-plates. Fig. 6 is a detail perspective view of the upper end of the harp. Fig. 7 is a detail perspective view of the body portion of the supplemental take-off. Fig. 8 is a detail perspective view of the cup with the carbon and copper plates therein. Fig. 9 is a detail section on about line 9 9 of Fig. 8, and Fig. 10 is an enlarged section illustrating the means for holding the conductor-blocks in connection with the upper ends of the harp-prongs.

An important object of my invention is to provide means for increasing the surface contact of the conduit or trolley-wire with the trolley in order to increase the take-off for the electric current passing through the wire and transmit the same to the motor on the car, whereby to increase the energy or force applied to the propulsion of the cars, so that the cars may be run faster or may carry heavier loads.

I provide a supplemental or auxiliary take-off, whose construction and operation will be more fully described hereinafter.

The trolley-arms A are of spring metal united at 1 and provided between such point of union and the bearings of the trolley-wheel

with a device such as shown in Figs. 2 and 3, whereby the arms may be positively forced away from or toward each other in order to increase or decrease the tension of the arms on the bearings for the wheel, as well as to spread such arms to facilitate the removal and application of the trolley-wheel, as may be desired. In the construction shown the arms A are provided with the inwardly-projecting screws B, secured at their outer ends to the arms A and projecting inwardly therefrom and reversely threaded, one of the screws B having a right thread and the other a left thread and receiving a turnbuckle C, which may be turned in one direction to draw the arms A together and 55 in the other direction to force the said arms apart. By this construction the tension of the arms on the wheel can be regulated and the arms can be spread apart for the purpose before described. The arms A are preferably 60 made of steel and are provided at their outer ends with the bearings for the wheel and are preferably constructed at such ends with the bosses a on their outer sides, surrounding the openings for the sleeve on which the wheel 65 turns. These bosses a are preferably of copper or other material of high conductivity and are on the outer sides of contact-blocks A', which are fitted in openings a' in the arms A. As shown in Fig. 4 and as better illustrated in 70 Fig. 10, the openings a' are slightly countersunk at their outer ends, as shown at a'', and the contact-block A' is fitted in the opening a' and is swaged out slightly into the countersunk portion a'' at the outer end of the opening a', so that the contact-blocks will be held rigidly to and practically swaged into contact with the arms A of the trolley, as will be understood from Figs. 4 and 10. At their inner ends the contact-blocks project inwardly 75 beyond the inner faces of the trolley-arms A and are encircled at such point by the ring-like heads D' on the upper ends of the conductor branches D, such heads D' being preferably swaged into contact and union with 80 the arms A in the practical embodiment of the invention. The bosses a on the outer ends of the contact-blocks A' form bearings on which rocks the supplemental take-off presently described, and such supplemental take- 85 90 95 100

off has positive electric connection through the contact-blocks and the heads D' with the conductor branches D, and the wheel E also has positive electric connection with the head-rings D' through the medium of the inner washer-plates F, which bear between the ends of the wheel and the said head-rings, as shown in Fig. 4. These inner washer-plates F have openings F', through which project the ends 10 of the sleeve G, on which the bushing of the wheel E turns. In securing the washer-plates from turning I provide studs H on the conductor branches, which fit in notches f in the edges of the plates F, so the latter will be held from turning. In assembling the parts 15 the plates F may be applied by fitting their notches f over the studs H and then turning the plates F until their openings register with the openings in the contact-blocks, when the 20 sleeve and the bolt or shaft I may be applied, as shown in Fig. 4.

The supplemental take-off is shown in detail in Fig. 7 and includes a contact J to run against the wire and a carrier K for said contact, such carrier being pivoted at K', so it 25 will rock concentrically with the axis of the trolley-wheel. In the construction shown the carrier includes the side arms K², of copper, which are provided with the rings K³, encircling the bosses a and held thereon by the washers L and the spring-keys L' or by other suitable means, as may be desired. The carrier has the upwardly - projecting portions 30 above its bearings K', which portions carry the contact and also has the downwardly-projecting portions k³, forming crank-arms carrying the bridle M, which may be rigidly secured thereto and which may be operated by its weight or by the weights suspended therefrom and also forms a convenient point of 35 connection for a rope by which the auxiliary take-off may be operated into contact with the wire, if desired. Ordinarily the weight of the bridle M or of a separate weight applied thereto, if desired, will serve to hold the contact J of the auxiliary take-off properly in 40 contact with the wire. The contact J includes, as shown, the carbon J' and the plates J² and J³, fitting in the box N, which latter is closed at its bottom N' and ends N² and N³, but is open at its ends N⁴, so the carbon and the copper plates J² and J³ may contact with the inner sides of the arms K² of the carrier. This box N is secured between the arms K² 45 by suitable rivets or other fastenings, as will be understood from Fig. 7, and the wall N² of the box slopes or is undercut on its inner face, and the screw N⁵ turns through the front plate N³ and operates to bind the parts in the 50 position shown in Fig. 9, and by withdrawing the screw N⁵ the plate J³ may be removed and the carbon J' and plate J² be then removed for renewal or for any other purpose desired.

65 It will be noticed that the auxiliary take-off

has its contact in the form of a brush movable along the conductor-wire in the use of the invention and increasing to a large extent the surface contact between the trolley and the conductor-wire. It will be readily seen that 70 the touch of the brush against the conductor-wire can be regulated in order to make same light or heavy, and this may be effected by varying the length of the steel bridle, greatly reducing the wear on the conductor-wire and 75 the brush and increasing the life of same, as the brush will be very sensitive to the most delicate touch of the wire.

Having thus described my invention, what I claim as new, and desire to secure by Letters 80 Patent, is—

1. The improvement in trolleys herein described comprising the harp having its prongs provided at their outer ends with bearings for the wheel, the turnbuckle device between the 85 said arms whereby they may be positively drawn together and spread apart, the outwardly-projecting bosses on the outer sides of the harp-prongs surrounding the axis of the wheel, the wheel, and the auxiliary take-off 90 having a carrier pivoted between its ends on the bosses on the harp-prongs and provided at its upper end with a contact and at its lower end with a stirrup.

2. The combination of the harp-prongs provided with outwardly-projecting bosses surrounding the axis of the wheel, the wheel between and journaled in connection with said prongs and the auxiliary take-off having a carrier pivoted on the bosses of the harp-prongs 100 and provided with a contact to move along the wire.

3. A trolley having a wheel and a carrier 105 rocking relatively to the wheel and provided with a brush-like contact to move along the conductor-wire.

4. The combination of the trolley-arms, inwardly-projecting studs or projections, the inner washer-plates having notches receiving said studs or projections, and openings for the 110 passage of the bearing devices for the wheel, such bearing devices, and the wheel.

5. A trolley having a trolley-wheel and an auxiliary take-off having a rocking carrier pivoted concentrically with the trolley-wheel, provided with a depending portion the weight of 115 which serves to hold the contact to the wire.

6. A trolley having a trolley - wheel and a supplemental take-off having a contact and a carrier therefor supported concentrically with 120 the trolley - wheel, and having a depending stirrup.

7. A trolley having a harp, a trolley-wheel and an auxiliary take-off having a contact device and a box therefor open at its ends and a 125 carrier therefor supported on the harp concentrically with the wheel, and having arms between which the box is secured.

8. A trolley having a supplemental take-off provided with a carrier pivoted between its 130

ends, a contact carried by the upper portion of the carrier, and means depending from the lower end of the carrier for operating the same.

9. The combination of the harp, the wheel, and the supplemental take-off having a carrier pivoted between its ends and having an upper portion carrying a contact, and a lower crank-like portion.

10. The combination of the harp-prongs, the contact-blocks secured to the harp-prongs and having the inner projecting portions and the outwardly-projecting bosses, the conductor branches having rings encircling the inner projecting portions of the contact-blocks, the wheel having electrical connection with the head-rings on the inwardly-projecting portions of the contact-block and the auxiliary

take-off pivoted on the outwardly-projecting bosses of the contact-blocks.

11. An auxiliary take-off for trolleys comprising the carrier-arms and the box held between said arms and open at its ends whereby the contact material supported in said box may contact directly with the carrier-arms.

12. The combination of the carrier-arms the box secured between the same and having an undercut face at one side, the plate fitting against such side, the plate fitting against the opposite side, a clamping-screw engaging the latter plate, and carbon between the said plates.
